VICTOR WILLOUGHBY, OF JEFFERSONVILLE, INDIANA, ASSIGNEE TO AMERICAN CAR AND FOUNDRY COMPANY, OF ST. LOUIS, MISSOURI, A CORPORATION OF NEW JERSEY.

VESTIBULE-TRAP-DOOR MECHANISM.

1,199,849.

Specification of Letters Patent.

Patented Oct. 3, 1916.

Application filed April 5, 1916. Serial No. 89,182.

To all whom it may concern:

Be it known that I, VICTOR WILLOUGHBY, residing at Jeffersonville, Clark county, Indiana, and being a citizen of the United States, have invented certain new and useful Improvements in Vestibule-Trap-Door Mechanism, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact 15 details of construction shown and described, as it is obvious that various modifications thereof will occur to persons skilled in the art.

In said drawings: Figure 1 is a longitudinal vertical sectional view taken outside of the top riser of the steps leading to the car vestibule, the trap door in said vestibule being shown in open position in dot and dash lines; Fig. 2 is a vertical central section through the door locking means and a portion of the trap door; Fig. 3 is a horizontal section through said locking device, being taken on the line 3—3 of Fig. 2; Fig. 4 is an elevational view of the latching end 30 of the locking device, showing the same mounted in the car platform, part of the plunger being broken away; and Fig. 5 is a detail view showing the operating arm in contact with the roller carried by the rearwardly extending arm of the hinge member that is attached to the door.

The present invention relates to trap door mechanism, such as is employed in the vestibule platforms of passenger cars, and 40 has to do with the provision of a trap door which may, or may not, be automatically raised from its usual horizontal position to a substantially vertical position adjacent the end sheathing of the car body. The arrangement is such that said trap door may 45 occupy its horizontal or closed position and be influenced toward opening, but restrained therefrom by suitable locking means. It is also the intention that the trainman may 50 readily release the door by actuating a plunger, either by pressing it with his foot or from underneath the car platform when the vestibule door is locked and entrance to the vestibule prevented.

55 One of the objects is to impart an initial

kick to the closed door to partially open the same, after which the automatic door opening means will carry it substantially, or entirely, to its open position. It is to be understood, however, that the automatic 60 door opening means may be omitted and that the initial impulse given to the door will raise it sufficiently so that the released edge may be grasped and the door manually 65 opened. The parts of the locking device are so automatically controlled that, after the release of the door, they resume their locking positions so that when the door is returned to its closed position, no further attention need be given it to insure its secure 70 retention.

Further objects of merit will become manifest hereinafter and are all parts of the present invention.

Referring to the drawings, 1 indicates the 75 top riser of the steps leading into the vestibule and 2 the end sheathing of the car, the said steps extending between the end sheathing and the built-up platform end sill 3. An angle 4 extends transversely of the car, the 80 vertical flange of which lies against the outer face of the end sheathing 2 and between angle 4 and platform end sill 3 is located a trap door 5, positioned to cover the steps in the usual manner. Said trap door 5 is stiffened by a hinge member 6 which has 85 a rearwardly and downwardly extending arm 7. An associated hinge member 8 is secured to angle 4 and pivotally connected with hinge member 6 attached to the door by a suitable pin 9. Stationary hinge member 90 8 contains a bearing 10 for a short shaft 11 which extends to another hinge member 8 (not shown), it being understood that any 95 number of hinges comprising the members 6 and 8 may be disposed along the hinged edge of the door, two of such hinges being commonly employed. At each hinge an operating arm 12 is keyed to the shaft 11 and 100 is so formed as to be in contact with a roller 7^a carried by the rearwardly extending arm 7 of the hinge member 6, whereby rotary movement of operating arm 12 will drive arm 7 of hinge member 6 forwardly, the hinge member 6 consequently raising the 105 door. An actuating lever 13 is also secured to shaft 11 and extends downwardly, the tension spring 14 being secured to its free end and extending forwardly to a hook bolt 15, retained in a bracket 16 110

2
secured to the inside of the top step riser 1. It is therefore evident that spring 14 exerts a pull upon the free end of actuating lever 13, thereby tending to rotate shaft 11. 5 When shaft 11 is permitted to rotate, *i. e.*, when the trainman operates the locking device 17, it partially revolves carrying with it operating lever 12. The latter, bears against the roller on rearwardly projecting 10 arm 7 of hinge member 6, revolves arm 7 about hinge pin 9 and the door stiffening hinge member 6 describes an upward arc, moving the door toward its open position.

After the exit and entry of passengers 15 the trap door 5 will be pushed down by the trainman to the full line position shown in Fig. 1, where it will be retained by the locking device 17. The relationship of the engaged edge of the trap door 5 and the mechanism of the locking device 17, which controls the door when it is in coöperative relation with said locking device, is an important part of this invention. The movable parts of the locking device 17 are 20 mainly housed in a casing 18, shown in the drawings to have a box-like structure provided with a depending cylindrical spring pocket 19. In the top wall of the casing 18 is a plunger aperture 20 vertically aligned 25 with the spring pocket 19. A plunger 21 passes through aperture 20, casing 18 and emerges from an aperture in the bottom of spring pocket 19. The upper end of plunger 21 is provided with a head 22 adapted 30 to receive the impact of the operator's foot, which head may be serrated to prevent slippage of the operator's foot which might render the plunger ineffective. After entering the upper part of the casing 18, the 35 plunger is of reduced diameter to form a shoulder 23. With its lower end seated in pocket 19, is a spring 24 which extends upwardly into the interior of the casing 18 and is surmounted by a washer 25. Appropriately spaced above washer 25 is another 40 washer 26, the upper face of which engages the annular shoulder 23 of plunger 21. Between washers 25 and 26 projects the bifurcated end of a lever 27 which, in its normal 45 position, slopes downwardly toward the open end of casing 18, projecting outside of said casing to form a kicker or impulse member 28 adapted to give an initial opening movement to the door, as hereinafter 50 described. A rivet 29 passes through the vertical side walls of casing 18 and lever 27, forming a fulcrum for the latter. Lever 27 is also provided with upstanding brackets or ears 30, spaced so that each continues upwardly from one side of said lever. A dog 55 or latch 31 is positioned between brackets 30 and is adapted to swing on a pivot pin 32 which has its bearings in the brackets 30. Latch 31 is provided with a depending 60 flange-like detent 33 which engages with a

coöperating upstanding detent 34 on the lever. The engagement between the detents 33 and 34 is maintained by a spring 35, the free ends of which are anchored in lever 27. From each anchored end the wire of spring 70 35 extends upwardly and contains helical convolutions, and after progressing beyond the convolutions said wire of the spring extends downwardly along the inner face of latch 31 in a continuous manner. Under the influence of spring 35 not only are detents 75 33 and 34 maintained in engagement, but the outer end of said latch 31 projects out of casing 18 and over the adjacent edge of the door when the latter occupies its closed 80 position. Thus the under or convex side of latch 31 and the upper exposed surface of impulse extension or kicker 28, form a pocket adapted to retain the door when it is in closed position. 85

Desiring to open the door, a trainman presses the head 22 of plunger 21 driving the latter downwardly. Plunger shoulder 23 carries upper washer 26 downwardly with the plunger, and the bifurcated end of lever 27 is depressed to substantially the dot and dash line position indicated in Fig. 2. As a result of this action, latch 31 and lever 27 being unified by spring 35, latch 31 90 swings about the axis of lever pivot 29 to 95 the dot and dash line position depicted in Fig. 2. As shown, latch 21 is substantially withdrawn into the casing 18. Substantially simultaneously with the withdrawal of latch 31, impulse extension or kicker 28 100 moves to engage the underside of the adjacent door edge and raise it a suitable distance, such as indicated by dot and dash lines in said Fig. 2. Where the door opening or raising mechanism previously described is employed, it will carry the door from the dot and dash line just referred to to substantially that indicated in Fig. 1. It is not always necessary to employ the automatic door opening means and when it is 105 omitted the extension 28 may be proportioned to raise the door such a distance that its outer edge may be grasped and the door swung to the vertical position shown in Fig. 1. The door having been carried past 110 latch 31, the trainman is free to release his foot from plunger head 22, whereupon the now compressed spring 24 will exert an upward thrust upon washer 25 and the bifurcated end of lever 27 will be raised automatically to the full line position shown in Fig. 2, and the locking device 17 will again be in its normal state. Passengers having boarded the car and it being desired to return the trap door to its horizontal position, 115 it is only necessary to push it to that position. Latch 31 is provided with an exposed beveled face 36 which is engaged by a door in closing and when so engaged the door pushes the latch inwardly against the in- 120 125 130 135

fluence of spring 35. The latter returns latch 31 to the full line position in Fig. 2 after the door has passed said latch. The adjacent door edge will then occupy the retaining pocket formed by latch 31 and impulse extension 28. Locking device 17 may be mounted in any appropriate manner, but preferably is provided with integral horizontal flanges 37, which are secured, as by screws, to the platform flooring of the platform end sill 3.

What I claim is:

1. In combination in a platform, a door under an opening influence when closed, and a door locking-and-starting device comprising door-impulse means and a door-latching contrivance carried thereby and operable independently thereof by said door in closing, said impulse means and latching contrivance acting as an integer to release and partly open said door.

2. In combination in a platform, a door, automatic door-opening means, and a door locking-and-starting device comprising initial impulse means for said door, and a door-latching contrivance carried by said impulse means to extend into the path of said door and operable independently of said impulse means by said door in closing and simultaneously therewith to release said door, said impulse means imparting an initial opening kick to said door.

3. In combination, a door, door-opening means influential when the door is closed, and a door locking-and-starting means comprising a rockable initial impulse member and a door-latching contrivance mounted thereon and adapted to be retracted by said door in closing and to retain said door in closed position, said starting member and latching contrivance being adapted to act as a unit to release and to impart an initial opening impulse to said door upon rocking said starting member.

4. In combination in a platform, a door under an opening influence when closed, and a door locking-and-starting device comprising a movable initial impulse member, a latch carried thereby and means normally projecting said latch into the path of said door, said latch being independently operable by said door in closing and unified with said impulse member upon movement of the latter, whereby said impulse member imparts an initial opening movement to said door and said latch is simultaneously withdrawn.

5. In combination in a platform, a door and a door locking-and-starting device comprising an initial impulse member, a latch carried thereby, and means normally projecting said latch into the path of said door and unifying said impulse member and latch at predetermined times, said latch being operable by said door in moving to a latch-

retaining position and said impulse member being adapted to withdraw said latch without relative movement therewith and to partly open said door.

6. In combination in a platform, a door and a door locking-and-starting device comprising an initial impulse member and a door retaining latch, and means so correlating the same that said latch is operable independently by said door in closing and can be withdrawn by movement of said impulse member without relative movement of said correlating means, latch and impulse member, the latter being adapted to partly open said door during the withdrawal of said latch.

7. In combination in a platform, a door and a door locking-and-starting device comprising a pivotally mounted impulse member, a door-retaining latch pivotally carried thereby, and means normally projecting said latch into the path of said door and so correlating said impulse member and latch that the latter is independently oscillated by said door in closing and both turned in unification about the axis of revolution of said impulse member, the latter partly opening said door and said latch being withdrawn, upon actuation of said impulse member.

8. In combination in a vestibule platform, an impulse member and a latch having door-confining portions, a trap door having a portion retained between said impulse member and latch confining portions when closed, said latch being independently operable by said door in closing and unified with said impulse member during movement thereof, whereby said door-confining portions of said latch and impulse members are withdrawn and caused to partly open said door, respectively.

9. In combination in a vestibule platform, a trap door and a door locking-and-starting device mounted adjacent the closed position of an edge of said door and comprising a casing, a lever pivoted therein and comprehending a rearwardly extending arm, a forwardly projecting door impulse extension and a latch support, a latch pivoted in the latter and resilient latch-projecting means, said latch being independently operable by said door in closing, an actuation of said rear lever arm causing said latch to be withdrawn substantially into said casing and said impulse extension to partly open said door.

10. In combination in a vestibule platform, a trap door and a door locking-and-starting device mounted on the platform and comprising a casing, a lever pivoted therein having a door-impulse extension projecting therefrom, a latch pivotally carried by said lever, means causing said latch to co-act with said impulse extension to form a door edge-retaining pocket, said latch being inde-

pendently operable by said door in closing and unified with said lever at other times, and operating means adapted to turn said latch and lever in unification to substantially withdraw the former into said casing and cause said impulse extension to partly open said door.

11. In combination in a vestibule platform, a trap door and a door locking-and-starting device mounted on the platform and comprising a casing, a lever pivoted therein having a door-impulse extension projecting therefrom, a latch pivotally carried by said lever, means causing said latch to 15 act with said impulse extension to form a door edge-retaining pocket, said latch being independently operable by said door in closing and unified with said lever at other times, and operating means adapted to turn 20 said latch and lever in unification to substantially withdraw said latch from a door-retaining position, to cause impulse extension to partly open said door and to return said latch and lever to their normal positions.

12. In combination, a door and a door locking-and-starting device comprising a pivoted lever provided with a door-impulse extension and a latch-support, an oscillatory latch pivoted to the latter, detents on said lever and latch adapted to mutually engage, and resilient means normally maintaining said detents in engagement but permitting independent operation of said latch by said door in closing, actuation of said lever causing the same and said latch to turn in unification whereby said latch releases the door and said impulse extension partly opens said door.

40 13. In combination, a door and a door

locking-and-starting device comprising a casing containing a spring pocket, a plunger passing through said casing, a spring surrounding the same and seated in said pocket, spaced followers slidable on said plunger, one being adapted to be driven thereby, a lever pivoted in said casing, operably engaging said followers and provided with a door-impulse extension and latch-carrying means, a resiliently pressed 50 latch adapted to be independently operated by said door in closing, and means for unifying said latch and lever, whereby operation of said plunger withdraws said latch, causes said impulse extension to partly open 55 said door and said spring returning the parts to their normal positions.

14. In combination, a door and a door locking-and-starting device comprising a casing containing a spring pocket, a plunger passing through said casing, a spring surrounding the same and seated in said pocket, lever actuating means responsive to said plunger and spring, a lever provided with an impulse extension and a latch, the latter being independently operable by said door in closing, and means for unifying said lever and latch at predetermined times, whereby operation of said plunger withdraws said latch, causes said impulse extension to partly open said door and said spring returning said latch, lever and extension to their normal positions.

In witness whereof I have hereunto set my hand in the presence of two witnesses. 75

VICTOR WILLOUGHBY.
